T. A. BAILEY

DENTIFRICE AND FLOSS CONTAINER

Filed Oct. 20. 1922

INVENTOR.
Theodore A. Bailey.

BY

Geo. P. Kimmel.
ATTORNEY.

UNITED STATES PATENT OFFICE.

THEODORE A. BAILEY, OF ORLANDO, FLORIDA.

DENTIFRICE AND FLOSS CONTAINER.

Application filed October 20, 1922. Serial No. 595,794.

To all whom it may concern:

Be it known that I, THEODORE A. BAILEY, a citizen of the United States, residing at Orlando, in the county of Orange and State of Florida, have invented certain new and useful Improvements in Dentifrice and Floss Containers, of which the following is a specification.

This invention relates to a dentifrice and floss container and has for its object to provide a device of such class, in a manner as hereinafter set forth, with means to provide floss and dentifrice containing compartments, the former arranged forwardly of and communicating with the latter whereby on the discharge of the dentifrice from its compartment, it will be caused to pass through the compartment containing the floss and impregnate the latter.

20 A further object of the invention is to provide a container for the purpose set forth having means, in a manner as hereinafter referred to, for retaining a coil of floss and further provided with means whereby the floss can be removed and severed in any length desired.

25 A further object of the invention is to provide a device for the purpose set forth, in a manner as hereinafter referred to, with floss and dentifrice compartments, and whereby the floss is held in its compartment, in such a manner as to form a discharge passage for the dentifrice.

30 A further object of the invention is to provide a container for the purpose set forth, in a manner as hereinafter referred to, with a neck portion forming a compartment for a coil of floss and further providing the neck portion with a cutter for severing the floss, when uncoiled, in any desired length.

35 Further objects of the invention are to provide a container for the purpose set forth which is simple in its construction and arrangement, strong, durable, compact, efficient and convenient in its use, readily assembled and comparatively inexpensive.

40 With the foregoing and other objects in view, the invention consists of the novel construction, combination and arrangement of parts, as hereinafter more specifically described and illustrated in the accompanying drawings, but it is to be understood that changes, variations and modifications can be resorted to which come within the scope of 45 the claims hereunto appended.

In the drawings wherein like reference characters denote corresponding parts throughout the several views:—

Figure 1 is an elevation of a container in accordance with this invention, 60

Figure 2 is an elevation, broken away, of a container in accordance with this invention, with the cover removed.

Figure 3 is a vertical sectional view broken away, of the top of the container, 65

Figure 4 is a top plan view of the container with the cover removed, and further illustrating a portion of the floss withdrawn,

Figure 5 is a section on line 5—5, Figure 4, illustrating the cutter for severing the floss. 70

Referring to the drawings in detail, 6 denotes the body portion of the container which has a closed bottom as at 7, and an open top. The body portion 6, at a point removed from the upper end thereof, is formed with a laterally disposed annular bead 8. Mounted on the open end of the body portion 6, as well as frictionally engaging therewith and extending to the bead 8, is a cap member 9, formed with a depending annular flange 10, which embraces the body portion 6, and the said cap member 9, is furthermore provided with a centrally disposed opening 11. Secured within the opening 11, is a vertically disposed casing 12, having an open top. The casing 12, is positioned against the wall of the opening 11, as well as depending within the cap member 9, and is formed with a concave bottom 13, having a centrally disposed opening 14, 75

whereby communication is established between the interior of the casing 12, and the compartment 15, formed by the body portion 6, and in which compartment 15, is arranged a body of dentifrice 16. The casing 12, forms a compartment 17, in which is positioned a coil of floss as indicated at 18. The diameter of the coil 18, is substantially the same as the inner diameter of the casing 12, and said coil 18, provides a discharge passage 19, and with the latter registering with the opening 14, so that when the dentifrice 16, is discharged from the compartment 15, it will pass through the coil of floss 18, and impregnate the floss as the dentifrice is discharged. 95

Frictionally engaging as well as inclosing the casing 12, is a cylindrical inverted cup shaped closure 20, having its top formed 100

110

2
with an opening 21, which registers with the passage 19. The closure 20, is flanged as at 22, and is forced on the cap member 9, and said closure 20, is furthermore provided with 5 a plurality of vertically disposed ribs 22, provided by offsetting said closure 20, and the latter at its top, is slit as at 24, and with the material freed by the slit 24, upset as at 25, to provide a cutter.

10 Removably mounted on the closure 20, as well as frictionally engaging therewith, is an inverted cup shaped cover 26, provided with a liner 27. The sides of the cover 26, frictionally engage with the ribs 23, where- 15 by the cover is retained in position, as well as spaced from the sides of the closure 20, as at 28, and into said space 28, the outer end of the floss is positioned as shown in Figure 3, and owing to the space 28, be- 20 tween the cover and the closure, which is formed by the ribs 23, the outer end of the floss 18, does not interfere with the pos- 25 titioning of the cover 26, when the container is to be closed. The inner end of the cover 26, is offset, as at 29, to overlap the flange 22.

From the foregoing description taken in connection with the accompanying drawings, a floss and dentifrice container is set 30 up, whereby the floss is positioned in the path of discharge of the dentifrice so that the latter passes through and impregnates the floss, and further the container is pro- 35 vided with means, to permit of the floss be- 40 ing severed at any length desired, and al- though the drawings illustrate the pre- fered embodiment of the invention, yet it is to be understood that details of the con- struction can be changed without departing from the spirit of the invention.

What I claim is:—

1. A container for the purpose set forth comprising a dentifrice compartment, a floss compartment arranged forwardly thereof 45 and communicating therewith for the dis- charge of the dentifrice, and a coil of floss mounted in said floss compartment and cap- able of being unwound and providing a discharge passage for the dentifrice.

50 2. A container for the purpose set forth

comprising means to provide a dentifrice compartment, a casing secured thereto and communicating therewith and providing a floss compartment, an apertured closure mounted on said casing, a cover mounted on the closure, and said closure provided with inherent means to constitute a cutter and further formed with inherent means for spacing the cover therefrom. 55

3. In combination, means to provide a 60 compartment containing a body of denti- frice, means arranged forwardly of said compartment and communicating therewith and providing a compartment containing a coil of floss forming a discharge passage 65 for the dentifrice, said coil capable of be- ing unwound, and a closure for the floss compartment, said closure having an opening to permit of the withdrawal of the floss and further having inherent means to con- 70 stitute a cutter for severing the floss into lengths desired.

4. A floss and dentifrice container com- prising means to provide a floss compart- 75 ment and a dentifrice compartment, the lat- ter arranged rearwardly of the former, means whereby the floss is impregnated by the dentifrice during the discharge of the lat- 80 ter from its compartment, a closure for the floss compartment, said closure provided with an opening for the passage of the floss and dentifrice, and a cover for said closure.

5. A floss and dentifrice container com- prising means to provide a floss compart- 85 ment and a dentifrice compartment, the latter arranged rearwardly of the former, means whereby the floss is impregnated by the dentifrice during the discharge of the lat- 90 ter from its compartment, a closure for the floss compartment, said closure provided with an opening for the passage of the floss and dentifrice, and a cover for said closure, said closure provided with inherent means to constitute a cutter for severing the floss in lengths desired and further having inherent 95 means for spacing the cover therefrom.

In testimony whereof I affix my signa- ture hereto.

THEODORE A. BAILEY.
